UNITED STATES PATENT OFFICE

171,247

CIGARETTE LIGHTER HOLDER

John Charnota, Chicago, Ill.

Application August 24, 1953, Serial No. 26,556

Term of patent 14 years

(Cl. D17—3)

To all whom it may concern:

Be it known that I, John Charnota, a citizen of the United States, residing at Chicago, in the county of Cook and State of Illinois, have invented a new, original, and ornamental Design for a Cigarette Lighter Holder, of which the following is a specification, reference being had to the accompanying drawing, forming a part thereof.

Fig. 1 is a front elevational view of a cigarette lighter holder, embodying my new design;

Fig. 2 is a rear elevational view thereof.

Fig. 3 is a cross-sectional view taken substantially on line 3—3 of Figure 1; and

Fig. 4 is a top elevation of Figure 1.

I claim:

The ornamental design for a cigarette lighter holder, substantially as shown.

JOHN CHARNOTA.
